US0D1099174S

(12) **United States Design Patent** (10) **Patent No.:** **US D1,099,174 S**
(45) **Date of Patent:** **** Oct. 21, 2025**

(54) **REAR PEDESTAL FOR CONCRETE MIXER**

(71) Applicant: **LMI US, LLC**, Rochester, MN (US)

(72) Inventors: **Jarud H. Hoefker**, Kasson, MN (US);
Clint Daniel Glunz, Rochester, MN (US);
Jacob Mitchell Holst, Austin, MN (US)

(73) Assignee: **LMI US, LLC.**, Rochester, MN (US)

(**) Term: **15 Years**

(21) Appl. No.: **29/927,541**

(22) Filed: **Feb. 5, 2024**

(51) LOC (15) Cl. **15-03**

(52) U.S. Cl.

USPC **D15/28**

CLAIM

The ornamental design for rear pedestal for concrete mixer,
as shown and described.

DESCRIPTION

FIG. 1 is an upper right front perspective view of the rear pedestal showing our new design;

FIG. 2 is an upper right rear perspective view thereof;

FIG. 3 is a lower right rear perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

1 Claim, 9 Drawing Sheets
